UNITED STATES PATENT OFFICE.

ABRAHAM H. ARONS, OF NEW YORK, N. Y.

DESIGN FOR A CABINET.

Application filed August 19, 1922. Serial No. 3,477. Term of patent 3½ years.

To all whom it may concern:

Be it known that I, ABRAHAM H. ARONS, a citizen of the United States, whose post-office address is No. 471 Seventh Avenue, borough of Manhattan, city and State of New York, have invented a new, original, and ornamental Design for a Cabinet, of which the following is a specification, reference being had to the accompanying drawing, forming a part thereof,

The figure displayed in the accompanying drawing is a perspective view of the cabinet showing my design.

I claim—

The ornamental design for a cabinet as shown.

Dated Aug. 15th 1922.

ABRAHAM H. ARONS.
